STOP MOTION FOR SPRING NEEDLE
KNITTING MACHINESEdward Vossen, Lynbrook, N. Y., assignor to
Stop-Motion Devices Corp., Brooklyn, N. Y., a
corporation of New York

Application August 16, 1949, Serial No. 110,598

7 Claims. (Cl. 66—159)

1

This invention relates to new and useful improvements in stop motions for spring needle knitting machines having a retractable presser foot for each yarn feed, of the type as embodied in the knitting machines of Tompkins Bros. and Crane, and other machines using spring beard needles.

On spring needle knitting machines, the spools or cones of yarn are usually run off the floor, or off wooden platforms, the yarn feeding upwards through porcelain guides directly into the feeds of the machines. Heretofore, stop motions have not been very successful on spring needle machines. For this reason there are large numbers of these machines operating without stop motions of any kind. There are several reasons why prior stop motions have been objectionable. To understand these objections it must first be noted that prior stop motions used on these machines included bottom knot and end detectors placed above the cones or spools, and top knot and end detectors placed high up over the machines. The yarns are threaded through the bottom detectors and then up to the top detectors high above the machines, and then down again into the feeds of the machines. Because the yarn runs from below to the top detectors and then down again into the feeds, there is undue tension on the yarns which affect the stitch, producing poor fabric because of the abnormal drag on the yarn caused by the fact that the top detectors are so high up. The reason that the top detectors are placed so high up is to allow sufficient slack in the yarn between the time that the controllers of the knitting machines knock off and the actual stopping of the knitting machines. Many of these knitting machines do not employ brakes and therefore the momentum carries the machines around completely. Without the use of a stop motion, a broken or loose end causes a complete press-off. Often the use of brakes on these particular types of machines is not feasible because the swing is so great that a sudden stop could damage the machines.

Another undesirable feature of the overhead type of detectors is that the yarns then form a picket fence around the machines in such a manner that the operator has to wade in between the threads in order to adjust the machines.

Another deficiency of the usual overhead detectors employed on these machines is that when the yarn is released from the overhead detectors it falls down on the machines and becomes twisted and entangled in the needles and feeds.

An important object of this invention resides

2

in the construction of a stop motion for spring needle knitting machines which does not require that the yarn be guided up over high top detectors. In fact, it is proposed that the new stop motion, in accordance with this invention, merely requires that the yarn extend from the spools or cones directly to the feeds of the knitting machines and no higher. This new stop motion eliminates the overhead detectors entirely. Because the yarn runs directly from the spools or cones to the feeds through suitable bottom and end detectors, the unwarranted drag of prior stop motions has been entirely eliminated, thus eliminating the prior poor work performed by these machines equipped with the old overhead type of detectors. With the new stop motion there are no picket fences of yarn around the machines so that the machines are readily accessible to the operator for adjustment and repair. Obviously, since the yarn does not extend above the knitting machines there is no possibility of the yarns dropping down and becoming twisted and entangled in the needles and feeds of the machines.

A characteristic of spring needle knitting machines resides in the fact that the needles are capable of throwing off the yarn stitches only as long as the presser feet are in engagement with the needles. This invention particularly proposes to provide a stop motion device capable of disengaging the presser feet from the spring needles upon the operation of any detector in order to prevent a press-off.

A further object of this invention resides in the provision of means for instantaneously cutting the yarn to a particular feed which causes the stop motion to operate in order to prevent the yarn from being fed into the knitted material after a particular feed has ceased to operate because its presser foot was retracted by the stop motion. This prevents visible damage to the knitted material. The fact that one feed ceases to operate does not produce a readily detectable defect.

The new stop motion, in accordance with this invention, is also provided with a master controller which instantly trips the starting handle of the knitting machine to cause the machine to come to a gradual stop, upon the operation of one or more of the detectors of the stop motion.

Another object of the invention is the construction of a device as described which is simple and durable and which may be manufactured and sold at a reasonable cost.

For further comprehension of the invention, and of the objects and advantages thereof, ref-

erence will be had to the following description and accompanying drawings, and to the appended claims in which the various novel features of the invention are more particularly set forth.

In the accompanying drawings forming a material part of this disclosure:

Fig. 1 is a plan view of a portion of a stop motion for a spring needle knitting machine constructed in accordance with this invention.

Fig. 2 is a fragmentary front elevational view of Fig. 1 illustrated with certain parts omitted for clearly showing the parts illustrated, a casing shown being broken away to disclose interior parts.

Fig. 3 is a sectional view taken on the line 3—3 of Fig. 2.

Fig. 4 is a fragmentary enlarged sectional view taken on the line 4—4 of Fig. 3.

Fig. 5 is a schematic wiring diagram of the device.

The stop motion for a spring needle knitting machine which has its cylinder of spring needles schematically illustrated and indicated in Fig. 1 by the dot and dash lines 10, has a retractable presser foot 11 for each yarn feed 12. In accordance with this invention the stop motion includes electric controlled means 13 (see particularly Fig. 5) for retracting each of said presser feet 11. An electric controller 14 is provided for stopping the knitting machine. The details of this controller 14 will not be given in this specification since it forms no part of the invention, and controllers of this type are generally known. The controller 14 includes a normally closed switch 15 when the controller is "on" and which opens when the controller snaps "off" to stop the knitting machine. A knot and end detector switch 16 is provided for each yarn for protecting the yarn feeds of the knitting machine, and these detector switches 16 are operated by the yarns of said feeds identically in the same way as the knot and end detector switches of present day stop motions on knitting machines. An electric circuit 18 connects said electric controller 14 with said electric controlled means 13, and with said detector switches 16 for operating one of said electric controlled means 13 and said controller 14 whenever the detector switch 16 of one of the yarns operates. A thread cutting means 20 is provided for each of the yarns to said yarn feeds 12 for cutting the yarn 21 to the particular feed 12 protected by the detector switch 16 which operated.

The presser foot 11 is mounted in the usual way upon a rod 22 adjustably mounted by an adjustment screw 23 on a plunger 24 which operates in the cylinder 25 mounted on a supporting bracket 26. In the "on" position, the presser foot 11 engages the spring needles 10 of the knitting machine. In the "off" position the pressure foot 11 is moved slightly to the left so as to disengage from the needles 10 of the knitting machine. In the latter condition the needles are incapable of throwing off the yarn and this prevents a press-off. When the presser foot 11 engages the needles, and a yarn is broken, the needles are capable of throwing off the yarn and a complete press-off occurs unless the knitting machine is stopped in time.

The detector switches 16 are normally held open by the yarn 21. As soon as a knot or other obstruction, or an end of the yarn reaches the detector switch 16 it closes, in order to operate the stop motion.

The electric controlled means 13 for retracting said presser foot 11 includes a yoke 30 connected with said presser foot 11 by engaging the bottom end of the rod 22. This yoke 30 is in the form of a strand of wire bent at the center. The bent center of said yoke 30 engages around said rod 22, said yoke 30 being disposed at right angles to the length of said rod 22. The yoke 30 is supported by having its ends mounted upon a bar 31. This bar 31 is fixedly mounted at its center across and upon a rack 32. The rack 32 is horizontally slidably mounted in a stationary bracket 33. A shaft 34 is turnably mounted in the bracket 33 and extends at right angles to the rack 32 and said shaft is provided with a pinion 35 engaging said rack 32 by which the rack 32 may be retracted. Said shaft 34 is resiliently urged to retract the rack 32 by a spring 36. The spring 36 is attached at one end by a screw 37 upon a bushing 38 mounted on the shaft 34. The other end of the spring 36 connects with a clip 39 mounted upon the bracket 33. A handle 40 is mounted upon one end of the shaft 34 by which said shaft 34 may be turned and the said electric controlled means 13 may be manually set in an "on" position.

The electric controlled means 13 also includes an electromagnetic latch for normally indirectly holding said yoke 30 forwards. This electromagnetic latch includes coils 42 with cores fixedly mounted on a bracket 43 attached to the bracket 33. An armature 44 is pivotally mounted by a trunnion or pintle 45 upon the bracket 43. This armature 44 is attracted by the cores of the coils 42 when the latter are energized. A leaf spring 46 mounted upon the armature 44 normally urges the armature 44 away from the cores of the coils 42. A stop finger 47 from the bracket 43 limits pivoting of the armature 44 away from the cores of the coils 42. A trip arm 48 is radially mounted on the shaft 34 and is engageable by and held by said armature 44 when the coils 42 are de-energized. The armature 44 is provided with an offset end 49 against which an inturned end 51 of the trip arm 48 engages. This offset end 49 is provided with a cam surface 50 against which the inturned end 51 of the trip arm 48 may engage when the electric controlled means 13 is manually moved to its "on" position by moving the handle 40.

The yoke 30 is associated with adjustable means for limiting its motion to its retracted position. This adjustable means merely comprises adjustments screws 52 threadedly mounted on the bar 31 and engageable against one face of the bracket 33. The electric controlled means 13 includes a selector switch 57 consisting of a contact arm 54 and two contacts, namely, an "on" contact 55 and an "off" contact 56. This selector switch 57 is mounted on an insulation strip 58 mounted on a support 59 attached to the bracket 33. The selector switch 57 is operated by a lever 53 engaging said trip arm 48 for holding said contact 54 upon said contact 55. Said switch 57 is provided with a spring 61 which moves the contact arm 54 upon contact 56 when the trip arm 48 is freed by said armature 44 and moves to its "off" position. A casing 60 is engaged upon each bracket 33 and covers the selector switch 57, the spring 36, the coils 42, the trip arm 48, and several other parts as may be readily seen by inspecting the drawing.

Each detector switch 16 is connected in series with the coils 42 of one of the electro-magnetic latches of its electric controlled means 13 for

retracting one of said presser feet 11. In the "on" position of the selector switches 57 the coils 42 of each of said means 13 is connected in parallel in said circuit 19. In the "off" position of each selector switch 57 the "off" contacts 56 are connected in parallel with each other and in series with said controller 14.

Each thread cutting means 20 includes a stationary tube 65 mounted upon the side of the casing 60. Each tube 65 has a porcelain eyelet 66 on one side through which the yarn 21 passes, and an aperture 67 diametrically opposite the eyelet 66 through which the yarn 21 also passes. A shearing knife 68 is cooperative with the aperture 67 for cutting the yarn 21. This shearing knife 68 has a hub portion 69 which is fixedly mounted upon one end of the shaft 34.

The operation of the stop motion for a spring needle knitting machine, in accordance with this invention, may be understood from the following:

The electric control means 13 are illustrated in "on" positions. The trip arm 48 is illustrated engaging the offset end 49 of the armature 44 representing the "on" position of the device. With the parts in this position the yoke 30 is in its forward position so that the presser foot 11 is in a corresponding forward position engaging the spring needles of the knitting machine. When the selector switches 57 are in their "on" positions the contact arms 54 engage the "on" contacts 55. The knitting machine may now be operated to knit material. Current does not flow in circuit 19 because the detector switches 16 are open.

Let us assume that a knot or other obstruction or an end of the yarn 21 comes along on one particular detector switch 16. Immediately this particular detector switch 16 is closed. The circuit 19 is now closed through one of the electric controlled means 13 for retracting one of said presser feet 11. The current flows through the coils 42 of this particular electric controlled means 13, causing the coils to magnetize its core, attracting the armature 44. The leaf spring 46 is merely flattened out when the armature 44 is attracted. The motion of the armature 44 drops the trip arm 48, freeing the shaft 34. Immediately the spring 36 turns the shaft 34 a small distance as permitted by the adjustment screws 52 striking the bracket 33. As the shaft 34 turns, the pinion 35 will move the rack 32, causing the yoke 30 to be retracted and correspondingly retracting the presser foot 11 of the particular yarn feed 12 affected. As soon as the presser foot 11 is retracted knitting at this particular feed ceases. This prevents a press-off.

The handle 53 of the selector switch 57 is released by the trip arm 48 and then spring 61 causes the contact arm 54 to engage the "off" contact 56, when the shaft 34 is turned by the spring 36. Now the electric circuit 19 supplies current to the controller 14 which instantly throws the starting handle of the knitting machine to its "off" position. When the shaft 34 was turned by the spring 36, the shearing knife 68 moved across the aperture 67 and sheared the yarn 21 to the particular feed 12 controlled by the particular presser foot 11 of the electric controlled means 13 which was just operated. Therefore, this yarn 21 of the particular feed 12 will not be wound around within the material being knitted by the other yarn feeds of the knitting machine.

The operator may reset the stop motion by moving to its "on" position the handle 40 of the

particular electric controlled means 13 which was operated by the particular detector switch 16, after said detector switch 16 is opened by threading the yarn 21 through said detector switch and the affected feed of the knitting machine. Then the controller 14 is reset to its "on" position. When the handle 40 is moved to the "on" position the shaft 34 was rotated to stretch the spring 36. Simultaneously the pinion 35 moved the rack 32 which moved the yoke 30 to its forward position. The trip arm 48 is moved by the shaft 34 so that the offset end 51 engages the cam 50, moving the armature 44 momentarily upwards while the offset end 51 engages behind the end 49 of the armature 44. The parts are now in their original positions.

While I have illustrated and described the preferred embodiment of my invention, it is to be understood that I do not limit myself to the precise 20 construction herein disclosed and the right is reserved to all changes and modifications coming within the scope of the invention as defined in the appended claims.

Having thus described my invention, what I 25 claim as new and desire to secure by United States Letters Patent is:

1. A stop motion for a spring needle knitting machine having a retractable presser foot for each yarn feed, comprising an electric controlled 30 means for retracting each of said presser feet, an electric controller for stopping said knitting machine, a detector switch for each of said electric controlled means for protecting its yarn feed and operated by the yarn of said feed, an electric circuit connecting said electric controller, said electric controlled means, and said detector switches for operating one of said electric controlled means and said controller whenever the detector switch of said one electric controlled means operates, 40 and thread cutting means for each of said feeds for cutting the yarn to the particular feed protected by the detector switch which operated, each of said electric controlled means including a yoke connected with its said presser foot, means 45 urging said yoke to retract said presser foot, and electro-magnetic means for normally holding said yoke forwards.

2. A stop motion for a spring needle knitting machine having a retractable presser foot for each yarn feed, comprising an electric controlled 50 means for retracting each of said presser feet, an electric controller for stopping said knitting machine, a detector switch for each of said electric controlled means for protecting its yarn feed and operated by the yarn of said feed, an electric circuit connecting said electric controller, said electric controlled means, and said detector switches for operating one of said electric controlled means and said controller whenever the detector switch of said one electric controlled means operates, 55 and thread cutting means for each of said feeds for cutting the yarn to the particular feed protected by the detector switch which operated, each of said electric controlled means including a yoke connected with its said presser foot, resilient means urging said yoke to retract said presser foot, and an electro-magnetic latch for normally holding said yoke forwards.

3. A stop motion for a spring needle knitting 70 machine having a retractable presser foot for each yarn feed, comprising an electric controlled means for retracting each of said presser feet, an electric controller for stopping said knitting machine, a detector switch for each of said electric controlled means for protecting its yarn feed and

operated by the yarn of said feed, an electric circuit connecting said electric controller, said electric controlled means, and said detector switches for operating one of said electric controlled means and said controller whenever the detector switch of said one electric controlled means operates, and thread cutting means for each of said yarn feeds for cutting the yarn to the particular feed protected by the detector switch which operated, each of said electric controlled means including a yoke connected with its said presser foot, resilient means urging said yoke to retract said presser foot, and an electro-magnetic latch for normally holding said yoke forwards, said resilient means including a rack connected with said yoke, a pinion engaging said rack, a shaft for said pinion, and a spring urging said shaft in one direction.

4. A stop motion for a spring needle knitting machine having a retractable presser foot for each yarn feed, comprising an electric controlled means for retracting each of said presser feet, an electric controller for stopping said knitting machine, a detector switch for each of said electric controlled means for protecting its yarn feed and operated by the yarn of said feed, an electric circuit connecting said electric controller, said electric controlled means, and said detector switches for operating one of said electric controlled means and said controller whenever the detector switch of said one electric controlled means operates, and thread cutting means for each of said yarn feeds for cutting the yarn to the particular feed protected by the detector switch which operated, each of said electric controlled means including a yoke connected with its said presser foot, resilient means urging said yoke to retract said presser foot, and an electro-magnetic latch for normally holding said yoke forwards, said resilient means including a rack connected with said yoke, a pinion engaging said rack, a shaft for said pinion, and a spring urging said shaft in one direction, and a handle mounted on said shaft by which said electric controlled means may be manually set in an "on" position.

5. A stop motion for a spring needle knitting machine having a retractable presser foot for each yarn feed, comprising an electric controlled means for retracting each of said presser feet, an electric controller for stopping said knitting machine, a detector switch for each of said electric controlled means for protecting its yarn feed and operated by the yarn of said feed, an electric circuit connecting said electric controller, said electric controlled means, and said detector switches for operating one of said electric controlled means and said controller whenever the detector switch of said one electric controlled means operates, and thread cutting means for each of said yarn feeds for cutting the yarn to the particular feed protected by the detector switch which operated, each of said electric controlled means including a yoke connected with its said presser foot, resilient means urging said yoke to retract said presser foot, and an electro-magnetic latch for normally holding said yoke forwards, said resilient means including a rack connected with said yoke, a pinion engaging said rack, a shaft for said pinion, and a spring urging said shaft in one direction, said resilient means including a rack connected with said yoke, a pinion engaging said rack, a shaft for said pinion, and a spring urging said shaft in one direction.

one direction, said electro-magnetic latch having a coil, and an armature attracted by said coil when energized, and a trip arm radially mounted on said shaft and engageable by and held by said armature when said coil is de-energized.

6. A stop motion for a spring needle knitting machine having a retractable presser foot for each yarn feed, comprising an electric controlled means for retracting each of said presser feet, an electric controller for stopping said knitting machine, a detector switch for each of said electric controlled means for protecting its yarn feed and operated by the yarn of said feed, an electric circuit connecting said electric controller, said electric controlled means, and said detector switches for operating one of said electric controlled means and said controller whenever the detector switch of said one electric controlled means operates, and thread cutting means for each of said yarn feeds for cutting the yarn to the particular feed protected by the detector switch which operated, each of said electric controlled means including a yoke connected with its said presser foot, resilient means urging said yoke to retract said presser foot, and an electro-magnetic latch for normally holding said yoke forwards, and adjustable means for limiting motion of said yoke to its retracted position.

7. A stop motion for a spring needle knitting machine having a retractable presser foot for each yarn feed, comprising an electric controlled means for retracting each of said presser feet, an electric controller for stopping said knitting machine, a detector switch for each of said electric controlled means for protecting its yarn feed and operated by the yarn of said feed, an electric circuit connecting said electric controller, said electric controlled means, and said detector switches for operating one of said electric controlled means and said controller whenever the detector switch of said one electric controlled means operates, and thread cutting means for each of said yarn feeds for cutting the yarn to the particular feed protected by the detector switch which operated, each of said electric controlled means including a yoke connected with its said presser foot, resilient means urging said yoke to retract said presser foot, and an electro-magnetic latch for normally holding said yoke forwards, said resilient means including a rack connected with said yoke, a pinion engaging said rack, a shaft for said pinion, and a spring urging said shaft in one direction, said thread cutting means including a knife connected with said shaft, and a member having an aperture through which said yarn passes, said knife shearing past said aperture when said electric controlled means operates to retract its presser foot.
